FRUIT AND VEGETABLE FILLING TABLE

Filed Feb. 21, 1935

UNITED STATES PATENT OFFICE

2,029,054

FRUIT AND VEGETABLE FILLING TABLE

Harry Burge, Celina, Ohio, assignor to Crampton
Canneries, Inc., Celina, Ohio, a corporation of
Ohio

Application February 21, 1935, Serial No. 7,651

1 Claim. (Cl. 226—69)

This invention relates to improvements in filling and inspection tables adapted for use in the semi-automatic packaging of fruit and vegetables in suitable containers.

5 The main object of the invention is to provide a filling table of this character in which the containers are fed by gravity to an inlet end of the table, and are moved thereafter intermittently toward the discharge end to permit proper filling
10 thereof.

Another object of the invention is to provide a device of this character with means for automatically feeding a predetermined quantity of liquid to each container during one of its periods of rest
15 in the filling table.

A further object is to provide a device of this character with means operated in alternation with the liquid filling means for moving the containers intermittently through the filling table.
20 Other objects of the invention will become apparent as the detailed description thereof proceeds.

In the drawing:

Figure 1 is a side elevation of the filling table;
25 Figure 2 is a top plan of the same;
Figure 3 is a vertical transverse section taken on the line 3—3 of Figure 1; and
Figure 4 is a fragmentary detail to an enlarged scale of part of the mechanism for effecting the
30 step-by-step movements of the containers through the filling table.

As shown in the drawing, the invention comprises skeleton frame-work designated generally by the reference numeral 1. This frame-work
35 comprises front standards 2, 3, and 4; and rear standards 5, 6, and 7. The standards 2, 3, and 4 are secured at their upper ends in proper spaced relation by means of a board 8, which forms the front wall of the filling table proper. The lower
40 ends of the standards 2, 3, and 4 are likewise secured in proper spaced apart relation by means of the angle iron runner 9.

The lower ends of the standards 5, 6, and 7 are secured in proper spaced relation in the frame-work by means of the angle iron runner 10; and the upper end of the standards 5, 6, and 7 are secured in spaced relation by means of the runner
45 11. The front and rear standards are secured together by suitable cross bars which are clearly shown in the drawing.

The table proper comprises a top 12 extending lengthwise of the framework and suitably supported at its opposite ends and intermediate the ends by transverse members of the framework.
50 This top 12 slopes downwardly toward the rear

standards 5, 6, and 7, and is connected at its rear edge to the back wall 13, which slopes upwardly from the top 12 and is suitably secured at its upper edge to the upper ends of the standards 5, 6, and 7. The top 12 not only slopes rearwardly of the framework, but is also slightly inclined toward the inlet end of the table, in order to cause the fruit juices to flow by gravity toward a discharge spout 14, which extends through the table 12 and conducts liquid flowing from the table top into a tank 15, suitably supported in the framework near the inlet end of the table.
5

The front edge of the top 12 has a board 16 suitably secured thereto. The boards 8 and 16 are spaced apart from each other at their lower ends to form in effect an open bottomed hopper arranged directly over a spout 17, which extends from the inlet end of the machine to the outlet end thereof, for the purpose of conducting overflow from the containers to the discharge end of the machine.
10 15 20

The inlet end of the machine is connected to a skeleton gravity conveyor 18 having an inlet 19 through which cans may be fed for movement by gravity toward the inlet station 20. The cans thus fed toward the station 20, are moved intermittently along a supporting rail 21 between guide rails 22, 23, 24, and 25 extending lengthwise of the table and suitably secured in the framework.
25

The intermittent movement above referred to is effected by means of a pusher plate 26 which is secured at right angles to a cut-off plate 27; both of which plates extend perpendicularly to a base plate 28, which in turn is suitably secured to a plate 29 extending from the upper end of supporting arms 30 and 31. The lower end of the arms 30 and 31 are secured to sleeves 32 and 33, slidably mounted on the rods 34 and 35, respectively. The rods 34 and 35 are secured at their outer ends to the vertical plate 36 of an angle iron having its horizontal plate 37 fixed to the upper end of angle braces 38 and 39, respectively, which have their lower ends suitably secured to a cross rail 40 fixed to the standards 4 and 7 near the lower ends thereof.
30 35 40 45

The plate 28 is suitably fixed to the cross bar 41 of a member designated generally by the reference character 42, fixed at its opposite ends to the sleeves 32 and 33, which as aforesaid, slide on the rods 34 and 35. The lower end of the member 42 is fixed to the piston rod 43, extending through a fitting 44, and is connected to pumping mechanism (not shown) enclosed in the pump cylinder 45.
50

The fitting 44 is connected at one end to a 55

5 pipe 46, which in turn is connected by an elbow 47 to a discharge pipe 48 extending from the bottom of the tank 15. The other end of the fitting 44 is connected by a pipe 49 through an elbow 50, standpipe 51, elbow 52, horizontal pipe 53, and elbow 54 to a pipe 55 for discharging liquid pumped from the tank 15 into any container which may be positioned directly below the pipe 55 on the runway 21.

10 The pump is operated by means of a motor 56 suitably supported on the framework and connected by a belt 57 to a driven pulley 58 having its shaft 59 journaled to rotate in suitable bearings 60 and 61 carried by the framework 1. The 15 shaft 59 extends through the bearing 61 and has the pinion 62 fixed thereto and in mesh with the large spur gear 63. The gear 63 is fixed to a shaft 64, the outer end of which has a crank arm 65 suitably secured thereto. The other end of 20 the crank arm 65 is pivoted to one end of a pitman 66, the other end of which is pivoted to the slide member 42 intermediate the ends thereof. The lower end of the member 42 is fixed to the 25 pump rod 43 and the arrangement is such that rotation of the crankshaft 64 causes a discharge operation of the pump simultaneously with the withdrawing operation of the pusher plate 26.

As usual in devices of this kind, the motor 56 is intended to run continuously. The shaft 64 30 is provided with a sleeve 67 notched to engage corresponding notches on a boss 68 formed at the end of the crank arm 65 where it is secured to the shaft 64. The clutch sleeve 67 is slidable into and out of engagement with the boss 68 by 35 means of the yoke lever 70 fulcrumed between its ends on a bracket 71, secured suitably to an angle iron support 72 forming part of the framework 1. The lever 70 is rocked about the fulcrum 71 by means of a link 72 pivoted at one 40 end to the lever 70 and at its other end to a crank arm 73 suitably secured to a crank shaft 74, which is journaled in the standards 2 and 3 and provided at its outer end with an operating handle 75.

45 A screen 76 is mounted toward the rear edge of the table 12 with its lower edge covering the outlet of the discharge spout 14. Hooks 77 at the upper edge of the screen engage the edge of

the back wall 13 to hold the screen in position. The screen 76 is intended to be readily removed from its position shown whenever it becomes necessary to wash off the top of the table 12.

In operation, the cans are fed by an operator 5 to the inlet end 19 of the gravity conveyor 18. The cans then move by gravity to the station 20, whence they are moved intermittently by the pusher plate 26 onto the horizontal runway 21. During this movement the cutoff plate 27 prevents the movement of any can from the conveyor 18 into the station 20. As the pusher plate 26 is moved outwardly from the inlet end of the machine, another can from the conveyor moves by gravity to the station 20. In the meantime, the row of cans on the runway 21 is stationary; and, during this period of rest the pump discharges a predetermined quantity of liquid from the tank 15 through the discharge spout 55 into the can immediately below it.

20 The intermittent movement of the cans gives the operator or operators sufficient time to fill the cans properly during their periods of rest. The filled cans may, of course, be capped manually after filling and while still on the runway 25 21; or they may be moved after discharge from the filling table to any other location for further processing or storage.

What I claim is:

A filling table comprising a frame having a 30 working table top adapted to support filling material, a guideway for receptacles extending along and at one side of one edge of said top, said top being inclined downwardly from said edge, a tank below said top, a gravity conveyor for moving 35 receptacles to the inlet end of said guideway, a pusher moving said receptacles from said inlet end on to said guideway, a pump connected to said tank for transferring liquid in measured quantities from said tank to a location directly 40 above said guideway, means for simultaneously operating said pump and pusher, said top having an aperture through the lower part thereof for conducting liquid by gravity from the material on said top into said tank and a screen on 45 said table top to prevent solid material passing through said aperture onto said tank.

HARRY BURGE.
